CLAIM

The ornamental design for a hair curler shield, as shown and described.

DESCRIPTION

FIG. 1 is a top, end, side perspective view of a hair curler shield showing my new design;

FIG. 2 is an end elevational view thereof, the opposite end being identical;

FIG. 3 is a side elevational view thereof, the opposite side being identical;

FIG. 4 is a top plan view thereof;

FIG. 5 is a bottom plan view thereof;

FIG. 6 is an end elevational view of a second embodiment thereof, the opposite end being identical;

FIG. 7 is a side elevational view thereof, the opposite side being identical;

FIG. 8 is a top plan view thereof;

FIG. 9 is a bottom plan view thereof; and,

FIG. 10 is a top, end, side perspective view thereof.

FIG. 2

FIG. 3

FIG. 4

FIG. 5

FIG. 1

FIG. 6

FIG. 7

FIG. 8

FIG. 9

FIG. 10
